UNITED STATES PATENT OFFICE.

DANIEL ALISON RADLEY, OF LAWRENCEBURG, MISSOURI.

COPY-BOOK, COPY-CASE, AND MOVABLE COPY-PLATE.

SPECIFICATION forming part of Letters Patent No. 295,941, dated April 1, 1884.

Application filed April 3, 1883. (Model.)

To all whom it may concern:

Be it known that I, DANIEL A. RADLEY, of Lawrenceburg, in the county of Lawrence and State of Missouri, have invented a new and Improved Copy-Book and Copy-Case and Mov-able Copy-Plates, to be used in learning or studying the art of penmanship; and I do hereby declare that the following is a full, clear, and exact description of the construction and operation of the same, reference be-ing had to the accompanying drawings, forming a part of this specification.

Figure 1 is a perspective view of my case, and Fig. 2 a view of a copy-plate.

15 The case is made of paper, leather, wood, or any material suitable for making book-covers, which it resembles. It consists of two leaves, A B, which are flexibly connected together at C, so as to fold one upon the other 20 when not in use, and to lie out flat, as in Fig. 1, when in use.

On the inner side of leaf A is formed a recess, c, to receive the copy-book. Adjacent to recess and upon opposite sides thereof are 25 secured hooks or clips b, to receive the ends of the copy-plates, which extend over the recess and hold the paper of the copy-book down smoothly. Buttons or other suitable fasten-ings may be employed in place of the hooks 30 or clips b.

On the inner side of leaf B are formed recesses e, to receive the copy-plates, and recesses f for the pen-holders or pencils. Buttons g, of thin material are pivoted to leaf B, 35 and serve to secure in place the plates and pen-holders. In leaf B are also formed recesses i, into which are extended the project-ing parts of hooks b when the case is closed, thus enabling the leaves to lie close together.

40 The copy-plates a consist of a thin brass, tin, or other metallic plate or slat of any other suitable rigid material, upon which is glued, pasted, or otherwise fastened a copy-slip, or

rather two copy-slips, one on each side of the plate. The copy-slips leave exposed the ends 45 of the supporting-plates, so that the slips will not be injured by the hooks b or the buttons g, nor be soiled in handling. These plates are arranged in a series, graded and numbered 1 2 3 4 5, &c., as shown at d in the drawings. 50 At h are shown copy-plates placed in posi-tion over the copy-book recess for writing.

In the case thus constructed there is pro-vided on leaf A a receptacle for the copy-book, which prevents the paper thereof from getting 55 torn, ruffled, dog-eared, or soiled while in use, and when the paper is all written upon it can be removed and its place supplied with new paper. On leaf B are provided convenient receptacles for the copy-plates and writing 60 implements, so that they are kept in order and are always convenient for use.

The leaves A B, when the case is not in use in writing, are folded closely together, and thus while the contents of the case are held in 65 position the whole are effectually preserved from soiling or other damage.

What I claim as my invention is—

1. The case recessed, as described, to re-ceive the copy-book, and provided with hooks 70 b, in combination with the copy-plates, by which the paper is held down smoothly.

2. The case consisting of the flexibly-con-nected leaves A B, provided with recesses c e f i, hooks b, and buttons g, all substantially 75 as described.

3. The copy-plate consisting of a rigid sup-porting-plate having secured to it, as de-scribed, the copy-slips, which leave exposed the ends of said plates, as and for the purpose 80 described.

DANIEL ALISON RADLEY.
